UNITED STATES PATENT OFFICE.

ROBERT PETMAN AND WILLIAM COATES LISTER, OF TORONTO, ONTARIO, CANADA.

LABEL OR TICKET HOLDER FOR BOTTLES.

1,410,220.

Specification of Letters Patent. Patented Mar. 21, 1922.

Application filed December 19, 1921. Serial No. 523,450.

To all whom it may concern:

Be it known that we, ROBERT PETMAN and WILLIAM COATES LISTER, British subjects, residing at the city of Toronto, in the county 5 of York and Province of Ontario, Dominion of Canada, have invented certain new and useful Improvements in Label or Ticket Holders for Bottles; and we hereby declare the following to be a full, clear, and exact 10 description of the same.

This invention relates to a bottle provided with a label or ticket holder formed by two circular members encircling the bottle neck having their opposed surfaces channeled to 15 receive the label or ticket, and provided with slots extending from the perimeters of the members to the channels for the entry therein of the label or ticket, as hereinafter set forth and particularly pointed out in the 20 claims.

In the drawings:

Fig. 1 is an elevational view of the bottle.

Fig. 2 is a fragmentary sectional elevation of the same, showing the label or ticket holding grooves in the beads or flanges surrounding the bottle neck.

Fig. 3 is a sectional plan view on the line 3—3 Fig. 1, and

Fig. 4 is a fragmentary view of a modification of the construction shown in the preceding figures.

Like characters of reference refer to like parts throughout the specification and drawings.

The present invention is particularly adapted for milk bottle purposes, but it is not intended that its use shall be confined to this type of bottle as it may be adapted to other uses of a like nature, and for that reason the bottle 1 may be of any usual or approved type. As the preferred use of the invention is for holding milk tickets, we have shown a structure of the milk bottle type in Fig. 1 of the drawings provided with the 10 usual circumferential bead 2 around the mouth of the bottle neck 3. At the base of the neck the bottle is formed with a second circumferential bead 4 encircling the neck and of approximately the same diameter as

the bead 2. The beads 2 and 4 are spaced from each other as shown in Figs. 1 and 2, the depth of the space being slightly less than the width of an ordinary milk ticket. Formed in the opposed surfaces of the beads 2 and 4 are annular channels or grooves 5 and 6 respectively into which the ticket is

entered. The distance between the inner surfaces of the grooves is approximately equal to the width of the ticket. For the entry of the ticket into the holder the bead 60 2 is formed with a diagonal slot 7 and the bead 4 is formed with a diagonal slot 8 extending through the beads to their respective channels 5 and 6. The ticket is entered through the slots 7 and 8 into the grooves or 65 channels 5 and 6 and worked forward until the whole of it is contained therein.

In the same way a label may be entered in the same grooves or channels and worked forward until it completely encircles the 70 neck between the beads 2 and 4.

The flanges or beads 2 and 4 are shown to be integral with the bottle neck, but it is possible to make the holder a separate device and fit it on the bottle as shown in Fig. 4. 75 In the latter case an annular band 9 is employed to encircle the bottle neck and at the top and bottom of this band are grooved or channeled beads or flanges 10 and 11 corresponding to the beads or flanges 2 and 4 and 80 provided with slots 12 and 13 for the entry of the ticket or label therein.

A construction of this kind provides a convenient means for preventing the inadvertent loss of milk tickets when the milk 85 bottles and milk tickets are set out for collection and for a further supply of milk.

Having thus fully described our invention, what we claim as new and desire to secure by Letters Patent is:

1. A label or ticket holder for bottles comprising two circular members encircling the bottle neck and having their opposed surfaces channeled to receive a label or ticket.

2. A label or ticket holder for bottles comprising two circular members encircling the bottle neck and having their opposed surfaces channeled to receive a label or ticket, and provided with slots extending from the perimeters of the members to the channels.

3. In a label or ticket holder for bottles, the combination of the bottle neck, two circular members, spaced from each other, encircling the bottle neck, and having their opposed surfaces channeled to receive a label 105 or ticket.

4. In a label or ticket holder for bottles, the combination of the bottle neck, two circular members, spaced from each other, encircling the bottle neck, and having their 110 opposed surfaces channeled to receive a label or ticket, and provided with slots extending

from the perimeters of the members to the channels for the entry therein of the label or ticket.

5. A label or ticket holder for bottles comprising an annular band, and two circular members spaced from each other encircling the bottle neck, said members having their opposed surfaces channelled to receive a label or ticket.

10 6. A label or ticket holder for bottles comprising an annular band, and two circular members spaced from each other encircling the bottle neck, said members having their

opposed surfaces channelled to receive a label or ticket, and provided with slots extending 15 from the perimeters of the members to the channels for the entry therein of the label or ticket.

Dated at the city of Toronto, this tenth day of December, A. D. 1921.

ROBERT PETMAN.
WILLIAM COATES LISTER.
